UNITED STATES PATENT OFFICE.

CHARLES FRANZ, OF HOLLIS, NEW YORK.

DESIGN COMPOSING AND REPRODUCING DEVICE.

Application filed September 1, 1925. Serial No. 53,961.

This invention relates to devices for creating or composing new and original designs or patterns.

The principal object of the present invention is to provide a device for creating or composing new and original designs or patterns made up of design elements embodied by blocks or units which may be conveniently arranged and rearranged in the design or pattern creating operation at the will of a person, and it may be utilized for determining color schemes without unnecessary waste of materials.

Another object of the invention is to provide means of the character described which may be used repeatedly and with which newly created designs or patterns may be reproduced and transferred.

The nature of the invention and its distinguishing features and advantages will appear when the following specification is read in conjunction with the accompanying drawings in which:—

Figure 1 is a view embodying the features and appurtenances of the present invention.

Fig. 2 is a sectional view taken substantially on the line 2—2 of Fig. 1.

Fig. 3 is a collective view of several blocks or units utilized for obtaining the design or pattern ensemble.

Fig. 4 is a view illustrating an ensemble of blocks embodying a new design or pattern, and showing one of the tracing papers in position for carrying out the design or pattern reproducing operation.

Fig. 5 is a view of a fragment of the tracing paper with the new design or pattern inscribed thereon.

In accordance with the present invention use is made of a folder 10 which consists of covers 11 and 12 which are hingedly connected as at 13. Arranged on the cover 11 is a chase or frame 14. Use is also made of a multiplicity of blocks or units 15 which may be of different sizes, but each of which is essentially of the same thickness. Certain of the units 15 have printed on one face thereof a design element 16, while certain other of the units 15 are without design elements and are used for filling the spaces between those units having the design elements thereon. If desired some of the units 15 may have more than one design element 16, that is to say each may have design elements on the opposite faces thereof. It is also to be understood that there will be similar design

elements on a number of units 15 to constitute a group so that more than one similar design element may be included in the design or pattern ensemble of the units 15. As shown in Figure 1, the units 15 are arranged at random in the frame 14 and completely fill the space between the sides of the frame. By removing the units 15 and rearranging them according to the fancy new and original designs or patterns may be created or composed as shown in Figure 4. When the units 15 are arranged in the frame 14 the upper face thereof will be flush with the sides of the frame 14 to present an even surface therewith. A sufficient number of units will be provided so that space or spaces between the units 15 having the design elements 16 thereon may be filled in to not only provide an even surface throughout but to maintain the units 15 having the design elements 16 thereon in the desired ensemble. The design elements 16 will be printed so that they may be easily traced, and said design elements may be merely in outline or may be an outline having therein a certain color or combination of colors.

In order that the newly created or composed design or pattern may be reproduced there is provided a plurality of sheets of tracing paper 17 which are arranged in folded condition at one side of the frame 14 so that one fold at a time may be arranged over the frame 14, as shown most clearly in Figure 4, for carrying out the tracing operation. In the present instance the sheets 17 are held in place by the use of a cord 18 whose opposite ends are attached to the frame 14. If desired the frame 14 may be attached directly to the cover 11, or as in the present instance the frame 14 may be removable.

It is to be understood that the folder 10, frame 14, and the units 15 may be made of any preferred material, such as stout cardboard, and that the units 15 may be of any size and shape with no limit to the number of units to be used.

From the foregoing it will be apparent that means are provided whereby new and original designs or patterns may be created or composed by the use of the units 15 which may be arranged and rearranged at the will of a person in the attainment of the new design or pattern; that the new design or pattern will be embodied by an ensemble of the units which will be maintained for carrying

out a tracing operation; and that color schemes may be worked out without incidental waste of materials and without requiring redrawing of the design or pattern since the newly created design or pattern will always remain until the units are again re-arranged.

I claim—

1. A device of the class described comprising a multiplicity of units of equal thickness, certain of said units having a design element printed on a face thereof, a chase for holding said units, and sheets of tracing paper carried by said chase at one side thereof.

2. A device of the class described comprising a multiplicity of units of equal thickness, said units being divided into groups, the

units of each group having a similar distinctive design element printed on one face thereof, a chase for holding said units, and sheets of tracing paper carried by said chase at one side thereof.

3. A device of the class described comprising a multiplicity of units of equal thickness, certain of said units having a design element printed on a face thereof, means for holding said units in the same plane with their upper faces flush with each other, said means comprising a rectangular frame, and a bottom for said frame on which the units rest; sheets of tracing paper carried by said frame at one side thereof, and a top hingedly connected to said bottom capable of being brought over said frame.

CHARLES FRANZ.
